TOBACCO STEMMER

Rupert E. Rundell, Rockville Centre, N. Y., assignor, by mesne assignments, to The American Tobacco Company, New York, N. Y., a corporation of New Jersey

Application May 1, 1935, Serial No. 19,228

23 Claims. (Cl. 131—57)

This invention relates to improvements in tobacco stemmers, its main object being to improve stemming machines of the general type disclosed in the co-pending application of T. R. Priddy, Serial No. 753,379, filed November 16, 1934, now Patent Number 2,114,457, although it should be understood that the various features of the invention are applicable to tobacco stemming machines of various types.

To this end it is an object of the invention to provide means for stemming any leaves which owing to broken stems or other causes are not held fast by the stem-pulling cables of the machine but carried along by the stemming mechanism without being stemmed.

Still another object is to provide means for scoring all stems which have been stripped, so that they will be broken off to a uniform length before their delivery from the machine, this length being adjustable within given limits.

A further object of the invention is to provide for relative adjustment of the cables which forward the leaves into the range of action of the butt-stripping unit and the cables which draw the butted leaves through the stemming mechanism to assure proper gripping thereof between the opposed runs of each set of cables, in order that the percentage of "dropped" leaves may be kept down to a minimum and also to permit separation of the cables for repair or replacement. Still another object is the provision of a mounting for the butt-stripping unit which will permit the same to be swung out of operative position for repair or replacement of the butt-stripping rolls. With these and other objects not specifically mentioned in view the invention consists in certain constructions and combinations hereinafter fully described and then specifically set forth in the claims hereunto appended.

The improved machine comprises a conveyor which delivers the leaves laid upon it by an operator to a set of cables having opposed runs which grip the advancing leaves between them and pull them forward through a set of carded rolls which strip the butt-ends of the leaves as they are carried along by the said holding cables. A second set of cables similar to the first grips the stem butts of the leaves emerging from the butt-stripping unit and draws them through a stemming unit consisting of an upper and lower endless carded belt set at a diverging angle to the second set of cables so that the leaf is gradually stripped off the stem as their divergence increases during the advance of the leaf. A delivery belt carries the stemmed leaves away from

the machine, and a conveyer discharges any unstemmed broken leaves which have been carried along by the stemming unit.

Both sets of cables in the present machine are made vertically and horizontally adjustable and the upper cable guides are so mounted that, by simply throwing a handle, they can be raised a given distance for convenient repair or replacement of the cables or their guides. The butt-stripping unit is mounted on a horizontally swingable bed mounted on a vertical pivot so that the entire unit can be swung free of the machine for inspection and repairs. The stemming belts are mounted so as to be horizontally and vertically adjustable, and the broken-leaf delivery belts, which are adjustable with the stemming unit, are in addition made transversely adjustable with respect to the stemming belts.

There is further provided mechanism consisting of a rotating disk carrying a plurality of grippers arranged to close upon the stem of any leaf broken off from its stem butt while the same is held in the belts, and pulling the same away from the latter and thereby stemming the broken leaf. This auxiliary stem puller is placed near the delivery end of the stemming unit at a point where the stems of all whole leaves have already been pulled out by the cables.

The device for scoring the stems consists of a vertically adjustable cutter disk co-acting with a fixed smooth roller placed parallel to the stemming belts in the meeting plane of the ends of the stemming pins to score the stems passing over the roller, thereby weakening them so that they all break off to the same length. The scoring disk is mounted on the guide for the upper stemming belt run and the roller is carried on the lower guide, both the disk and roller being movable in the direction of the stemming belts to permit variation of the distance of the scoring point from the holding cables.

In the accompanying drawings which form a part of this specification and in which like characters of reference indicate the same or like parts:

Fig. 1 is a plan view of the butt-stripping section of the machine;

Fig. 1a is a sectional view taken on line 1a—1a, Fig. 1, showing the adjusting mechanism for the carded butting rolls.

Fig. 2 is a plan view of the leaf-stemming section of the machine;

(Figs. 1 and 2, when joined on the line I—I, constituting a complete plan view of the improved machine.)

Fig. 3 is a cross-section through the idler sheaves of the primary set of cables, taken on line 3—3 of Fig. 1, showing the vertical and horizontal adjustment of the sheaves, this cross-section being identical with that taken on line 3'—3' of Fig. 1, of the idler sheaves of the other set of cables, with the exception of the lengths of the sheave axles and their bearings;

Fig. 4 is a cross-section of the cable guides on line 4—4 of Fig. 1, showing the device for raising the upper cable, this cross-section being identical with the section on line 4'—4' of Fig. 1 and similar to the section on line 4''—4'' of Fig. 2;

Fig. 5 is a vertical cross-section of the cable guides on line 5—5 of Fig. 1, showing the device for latching the upper cable and its guide sheave in raised position, this cross-section being similar to the section on line 5'—5' of Fig. 2;

Fig. 6 is a cross-section of the cable drive on line 6—6 of Fig. 1, showing the vertical adjustment of the driving sheaves, this cross-section being identical with the section on line 6'—6' of Fig. 2;

Fig. 7 is a cross-section of the stemming-belt drive, taken on line 7—7 of Fig. 2 and showing the devices for vertically adjusting the stemming belts and transversely adjusting the broken-leaf delivery belts;

Fig. 8 is a detail view from line 8—8 of Fig. 7, showing the arrangement for vertically adjusting the stemming belt sprockets;

Fig. 9 is a sectional elevation of the auxiliary stem puller for stemming broken leaves broken off from the holding cables, the same being taken on line 9—9 of Fig. 2;

Fig. 10 is a front elevation of the adjustable stem scorer as viewed from line 10—10 of Fig. 2; and

Fig. 11 is a side elevation of the stem scorer viewed from line 11—11 of Fig. 10.

In carrying the invention into effect there is provided butt-stripping mechanism, mechanism for advancing leaves into the range of action of said butt-stripping mechanism, carded traveling endless surfaces adapted to strip the lamina from the stems of leaves drawn therebetween, means for gripping the stem butts of the leaves after they have been subjected to the action of said butt-stripping mechanism and drawing them between said carded surfaces, and a device for scorning at a predetermined length the stems of leaves drawn between said carded surfaces by said means so that each unbroken stem will be broken off at its scored portion. In the best constructions contemplated, there is provided a rotary disk having sets of grippers coacting to seize the stems of leaves which have broken off from the stem butts gripped by said means and pull said stems between said carded surfaces to strip them. The means above referred to may be widely varied in construction within the scope of the claims for the particular machine selected to illustrate the invention is but one of many possible embodiments of the same. The invention, therefore, is not to be restricted to the precise details of the structure shown and described.

Referring to Figs. 1 and 2, of the drawings, the belts 15 and 16 are driven by pulleys 17 and 18 on shaft 19. The upper runs of the belts travel over a table 20, and the leaves L placed thereon by an attendant are advanced until they are gripped between the opposed runs of upper and lower endless cables 21 and 21' driven from a motor 22 by sheaves 23 on shafts 24 and 24', respectively, and running over idler sheaves 25 and

25' on shafts 26 and 26'. The cables 21 and 21' are looped over their driving and idler sheaves a plurality of times to provide a plurality of operating runs on each cable, as fully described in the Priddy application referred to above; and the crossing run of each cable passes over guide sheaves 27 carried by brackets 28. Thereupon the cables 21 and 21' advance the leaves with their butts projecting into the space between two superimposed spirally carded rolls 29 which are set at a diverging angle from the cables and driven by a motor 30 whereby the butt-ends of the leaves are stripped.

After passing the rolls 29, the stems S of the leaves L are gripped between a set of cables 31 driven from a motor 32 by sheaves 33 on inclined shafts 34 and running over idler sheaves 35 on inclined shafts 36. The cables 31 are likewise looped over their driving and idler sheaves a number of times to provide a plurality of opposed runs, and their crossing runs pass over guide sheaves 37 carried by brackets 38. The cables 31 are laterally offset from but parallel to the cables 21 and 21' and act to draw the leaves L through the gap between the opposed runs of the 25 carded stemming belts 39, the lamina being thus stripped off the stems by the carding pins of the stemming belts which travel in the forward direction with respect to the movement of the leaves. These stemming belts 39 are sufficiently inclined away from the cables 31 to permit their carding pins to strip the leaves, and are fastened to endless chains driven from a motor 40 by sprockets 41 on shafts 42 and run over idler sprockets 43 on shafts 44, this construction of 35 the stemming belts being fully shown in the Priddy application cited above.

Whenever the stems of the leaves being advanced by the cables 31 are broken off, the unstemmed or partially stripped leaves thus left between the stemming belts 39 are carried along by the same; and if their broken stems project sufficiently above the belts 39, are caught by the grippers of the auxiliary stem puller 45 which by its rotary movement pulls the stems S' out of 45 the stemming belts, thereby stripping the same. In case the broken stems of the unstemmed leaves do not project sufficiently above the belts 39 to be engaged by the grippers of the stem puller 45, they are carried on by the stemming belts 39 to 50 a pair of endless conveyor belts 46 which advance them out of the machine. The belts 46 are driven by pulleys 47 on shafts 42 and run over idler pulleys 48 on shafts 49 carried by brackets 50 attached to the frame of the stemming machine. The stems S are deflected from the stem puller by a guard 45a.

Ordinarily, the stems S, when properly gripped by the cables 31, break off close to the leaf within the width of the carded sections of the belts 39, the stripped length of the stems varying with the length of the leaves and the toughness of their stems. If it is desired to break all stems to the same length, the scorer 51, hereinafter described is attached to the machine and is adjusted to the proper position so that the stems are all weakened at the same distance from the cables 31. This feature is highly desirable since it permits the production of a type of "strip" preferred by some manufacturers.

Referring now to Fig. 3, the shaft 26 of the idler sheave 25 of the upper cables 21 is supported in bearings 52 hung by an eye-bolt 53 from a bracket 54 mounted on horizontal guides 55 and 56 attached to the side frame 51 of the stem- 75

ming machine. The bracket 54 is slideable on the guides 55 and 56 and may be adjusted thereon by turning a screw 58, Fig. 1, loosely held in frame 57 and engaging with a threaded lug 59 of bracket 54, thereby providing lateral adjustment of the bearing 52 with the shaft 26. The eye-bolt 53 has a threaded portion engaging a threaded bore in a bevel gear 60 seated on the bracket 54 and meshing with a bevel gear 61 having an axle 62 journaled in the cover plate 63 of bracket 54. By turning the shaft 62 of gear 61 by means of a crank handle (not shown), the bearing 52 can thereby be raised or lowered in bracket 54 for vertical adjustment of the upper sheave-shaft 26. The shaft 36 of the idler sheave 35 of the upper cable 31 is similarly mounted in a bearing adjusted vertically and horizontally on the side frame 57.

The bearing 64 of the shaft 26' of the idler sheave 25' is supported by an adjusting screw 65 threaded in a bracket 66 slideable on guides 56 and 67, thus affording lateral and vertical adjustment of lower sheave-shaft 26'. During its vertical adjustment the bearing 52 is guided by sliding engagement of its lateral extensions 52' with guides 68 attached to brackets 54, see Fig. 1. Similar provision is made for vertically and horizontally adjusting the idler sheave 35 of the lower cable 31. After the desired adjustment of sheaves 25, 25' and 35 has been made, the fastening screws of guides 55, 56, 67 and 68 are tightened to retain the bearings 52 and 64 in the adjusted position. Fastening screws 68a hold guides 68 in proper position.

The lower run of the upper cable 21 is engaged by bars or guides 69, Fig. 4, attached to slotted holders 70 slideable on pins 71 carried by sockets 72 fastened to brackets 73. Adjustable coil springs 74 seated in the sockets 72 bear on holders 70 to press the underlying run of the cable 21 against the leaves on the opposed run of the cable 21' and retain the same thereon. The brackets 73 are joined by links 79 to levers 80 fixed on a shaft 81 journaled in brackets 75 and carrying a hand lever 82. By swinging the latter out of its normal position in the direction of the arrow, Fig. 4, the brackets 73 can be raised simultaneously, thereby lifting the guide 69 off the cable 21 and giving access to the same as well as to the lower cable 21' and its guide 69' which is attached to a bar 83 carried by brackets 84 on frame 57. Clamps 76 fixed to rods 77 located in suitable bearings in the frame of the machine are adjusted by hand wheels 78 or like devices to bear against brackets 73, and secure them in adjusted position relative to lower brackets 84.

To retain the brackets 73 in either raised or lowered position when the clamps 76 are open, the bracket 75 in which the mid-section of the shaft 81 is mounted, Fig. 5, carries a plunger 85 which is pressed by a spring 86 into one of two holes in a bracket 87 adjustably attached by a socket 88 and screw 89 to the holder 79 of cable guide 69. By pulling a knob 90 attached to the free end of plunger 85, the latter is withdrawn from bracket 87 so that the same can be raised by handle 82 into its upper position, whereupon the plunger 85 snaps back into bracket 87, the lower hole then having reached the position formerly occupied by the upper hole, as shown by the arrow.

The opposed runs of the cables 31 are similarly engaged by bars or guides 69'', the lower bar 69'' being stationarily supported in the same manner as guide 69' just described; and the upper bar

69'' being yieldingly supported from brackets carrying a shaft 81' which is connected to the said brackets by linkage (not shown) and provided with a hand lever 82', and fastened in operative position to cause the stem butts of the leaves to be gripped between the cable runs traveling through the bars 69'', by means of clamps (not shown) controlled by hand-wheels 78' (Fig. 2). To latch the upper bar 69'' in operative or raised position when the hand-wheels are turned to release the upper bar 69'', there is likewise provided a spring-pressed plunger 90', and upon lifting the hand-lever 82' the upper bar 69'' will be raised.

The shafts 24 and 24' of the driving sheaves 23 and 23' of the cables 21 and 21' are vertically adjustable as shown in Fig. 6. A gear transmission of conventional construction driven from the motor 22 and comprising two shafts 92 and 93 carrying sprockets 94 and 95 which by chains 96 and 97 running over yieldingly mounted tightener sprockets 168 are connected to the driving sprockets 98 and 99 of shafts 24 and 24', respectively. The bearings 100 of shaft 24 are supported by brackets 101 hung by eye-bolts 102 from a cross-member 103 supported by the side frames 57 and 57' of the stemming machine. The eye-bolts 102 supporting the bearings for the ends of the shaft 24 are screwed into bevel gear 104 meshing with bevel gear 105 on the ends of a shaft 106 journaled in member 103, as illustrated in Fig. 6. The gear 104 at the outer end of eye-bolt 102 also meshes with a bevel gear 107 journaled in end plate 108 of cross-member 103, its axle 109 being made with a square end for the reception of a crank handle. By thus turning gear 107, by means of the crank handle the eye-bolts 102 at the two ends of shaft 24 are raised or lowered in unison for vertical adjustment of shaft 24. The brackets 101 have lateral extensions 101', Fig. 1, sliding in guides 110 attached to side frame 57'. The bearings 111 of the lower shaft 24' are carried by brackets 112, Fig. 6, which rest on adjusting screws 113 turning in lugs 114 attached to frame 57' and providing vertical adjustment of the shaft 24'.

The carded butt-stripping rolls 29, Fig. 1, are supported by sets of brackets 115, 115' pivoted on pins 116a on pedestals 116, 116' mounted on a bed 117, the brackets 115 of the upper as well as the brackets 115' of the lower roller being adjustable vertically on their pivots by means of adjusting screws 118 threaded in spaced lugs fixed on pedestal 116. After adjustment to proper position by screws 118 brackets 115, 115' are locked in adjusted position by means of bolts 115a which extend through slotted ends of brackets 115, 115' and pedestals 116, 116'. The bed 117, which also carries the motor 30 driving through a gear transmission housed in the transmission box 119 shafts carrying sprockets 120, is swingably supported by a vertical shaft 121 held in a bracket 122 attached to side frame 57, and in the embodiment shown is adapted to be swung manually about shaft 121. On its bottom the bed 117 has rollers 123 resting on a curved bracket 124 on frame 57, so that the entire butt-stripping unit can easily be swung clear of the machine in the direction of the arrow (Fig. 1).

The shafts 44 of the idler sprockets 43 of the stemming belts 39 are supported by brackets 125, Fig. 2, arranged similarly to the brackets 54 and 66 in Fig. 3, for vertical adjustment of

the stemming belts. The sprockets 43 are also axially adjustable by means of a handwheel 126, Fig. 2, which turns a bevel gear 127 meshing with a bevel gear 128 on one end of a horizontal screw-shaft 129, the said screw-shaft engaging with a threaded member 130 slideable vertically on the supporting bracket of the upper sprocket 43. A bevel gear 131 on the other end of shaft 129 meshes with a bevel gear 132 on the upper end of a vertical shaft 133 which has a second bevel gear on its lower end driving a lower screw shaft engaging with a threaded member similarly slideable vertically on the supporting bracket of the lower sprocket. Both sprockets 43 thus move in unison during their axial adjustment and thus the receiving end of the stemming belts may be readily moved away from the cables 31 to provide access for repair and replacement of the belts and their driving chains.

The bearings 134, 134' of the shafts 42, 42' of the driving sprockets 41, 41', Fig. 7, are supported by eye-bolt 135 and adjusting screws 135a on brackets 136, 136' slideable on a pedestal 138, and may be vertically adjusted in the same manner as the bearings 52 and 64 in Fig. 3. The brackets 136, 136' have threaded lugs 137, Fig. 8, into which are fitted the screws 138 which are free to turn in the pedestal 139 for transverse adjustment of the driving sprockets. On the outer ends of the shafts 42, 42' are mounted sprockets 140, 140' driven from sprockets 141, 141' on shafts 142, 142' of a gear transmission of well known construction housed in the transmission box 143 of the motor 49 by driving chains running over adjustable idlers 144, 144'. The sprockets 41, 41' are made with long hubs overhanging the bearings 134, 134', and on these hubs are slidably mounted, by means of keys 145 fitting into long keyways 145' therein, the driving pulleys 47, 47' of the broken-leaf conveyor 46 which thus are laterally adjustable with respect to the stemming belts 39.

The auxiliary stem puller for broken leaves above referred to consists of a rotary disk 146, Fig. 9, around the circumference of which are mounted pairs of gripping jaws 45, 45', the movable jaws 45 being fulcrumed on horizontal studs 147 carried by lugs on the stationary jaws 45'. The jaw 45 of each pair is pressed against the jaw 45' by compression springs 148 and carries a roller 149 engaging with a stationary cam 150. The latter is so shaped that the jaws 45 close as they enter between the stemming belts 39 and 39' to grip the stem of any broken leaf L' which may project from the carding pins and open as they approach a stripping wheel 151, allowing the latter to enter between them to eject the stripped stem. The shaft 152 of disk 146 is driven by bevel gears 165 and 166 from a shaft 167 independently driven by suitable conventional means supported by the end frame 153 of the stemming machine.

While the stemming belts may diverge sufficiently from the cables 31 to entirely strip the stem, it is preferred to leave some of the stem in the leaf at the tip of the same, as some manufacturers wish to make use of this portion of the stem. To this end there is provided a stem scoring device, Figs. 10 and 11, consisting of a cutter disk 51 placed in the path of the advancing stems S of the leaves L carried by the stemming belts 39, 39', and of a smooth roller 154 underlying the disk. The shaft 155 of the scoring disk 51 is supported in a bearing 156 vertically slideable in a

bracket 157 mounted on the guide 69'' of the upper stemming belt 39. The bearing 156 is supported by a screw 158 threaded into the bracket 157, and may be thereby adjusted to score the stems so that they will be broken off at their scored portions, leaving "strips" in which the lamina will extend beyond the stem portion at either side thereof, this type of "strip" being preferred by the manufacturers. On the shaft 155 of the disk 51 is mounted a sprocket 159 driven through a chain 160 from a sprocket from a suitable source of power. The shaft 161 of roller 154 is supported by a bracket 162 mounted on the guide 69'' of the lower stemming belt. This shaft extends beyond the holding cables 31, 31' and is driven by a sprocket 163 through a chain 164 from a second sprocket on the shaft of the motor which drives the cutter disk 51. The brackets 157 and 162 are adjustably fastened to the guides 69'', 69''', by screws passing through slots in the brackets, so that the stem scorer can readily be adjusted for different lengths of stems. The chains 160 and 164 run over adjustable idlers which can be set to take up their slack in the different positions of the scoring unit.

Since the scored portions of the stems are broken off between the carded sections of the stemming belts, the stem portions remaining in the leaves are retained therebetween, and thus the "strips" are delivered from the end of the machine to any suitable receiving or conveying means, not shown. Any leaves which break off from their stem butts while the latter are gripped by cables 31 are stemmed by the auxiliary stem puller and delivered from the stemming belts together with the "strips". If the stem puller fails to grip the broken stem of any leaf, the same will be carried between the belts 46 and thereby separated from the "strips".

What is claimed is:

1. In a tobacco stemming machine, the combination with butt-stripping mechanism, of mechanism for advancing leaves into the range of action of said butt-stripping mechanism, carded traveling, endless surfaces adapted to strip the lamina from the stems of leaves drawn therebetween, means for gripping the stem butts of the leaves after they have been subjected to the action of said butt-stripping mechanism and drawing them between said carded surfaces, mechanism having sets of opposed grippers co-acting to seize the stems of leaves which have broken off from the stem butts gripped by said means and pull said stems between said carded surfaces to strip them, and a device for scoring at a predetermined length the stems of the leaves drawn between said carded surfaces by said means so that each unbroken stem will be broken off at its scored portion.

2. In a tobacco stemming machine, the combination with butt-stripping mechanism, of mechanism for advancing leaves into the range of action of said butt-stripping mechanism, carded traveling, endless surfaces adapted to strip the lamina from the stems of leaves drawn therebetween, means for gripping the stem butts of the leaves after they have been subjected to the action of said butt-stripping mechanism and drawing them between said carded surfaces, mechanism having sets of opposed grippers co-acting to seize the stems of leaves which have broken off from the stem butts gripped by said means and movable substantially in the plane of the leaves carried by said carded surfaces to pull said stems between said carded surfaces and thereby strip them, said

carded surfaces including belts having opposed runs arranged to strip leaves drawn therebetween by said means and diverging from the latter.

3. The combination with carded traveling, endless surfaces adapted to strip the lamina from the stems of tobacco leaves drawn therebetween, of means for gripping the stem butts of tobacco leaves and drawing them between said surfaces to strip them, and a rotary disk having sets of opposed grippers coacting to seize the stems of leaves which have broken off from the stem butts gripped by said means and pull said stems between said carded surfaces to strip them.

4. The combination with carded traveling, endless surfaces adapted to strip the lamina from the stems of tobacco leaves drawn therebetween, of means for gripping the stem butts of tobacco leaves and drawing them between said surfaces to strip them, mechanism having sets of opposed grippers coacting to seize the stems of leaves which have broken off from the stem butts gripped by said means and movable substantially in the plane of the leaves carried by said carded surfaces to pull said stems between said carded surfaces and thereby strip them, and mechanism for actuating said grippers to seize and subsequently release said stems.

5. The combination with carded traveling, endless surfaces adapted to strip the lamina from the stems of tobacco leaves drawn therebetween, of means for gripping the stem butts of tobacco leaves and drawing them between said surfaces to strip them, mechanism having sets of opposed grippers coacting to seize the stems of leaves which have broken off from the stem butts gripped by said means and pull said stems between said carded surfaces to strip them, mechanism for actuating said grippers to seize and subsequently release said stems, and a rotary member entering between said grippers for ejecting the released stems from said grippers.

6. The combination with carded traveling, endless surfaces adapted to strip the lamina from the stems of tobacco leaves drawn therebetween, of means for gripping the stem butts of leaves and drawing them between said surfaces to strip them, mechanism for seizing the stems of leaves which have broken off from the stem butts gripped by said means and pulling said stems between said carded surfaces to strip them, and a device for scoring at a predetermined length the stems of the leaves drawn between said carded surfaces by said means so that each unbroken stem will be broken at its scored portion.

55 7. The combination with mechanism for stripping the lamina from the stems of tobacco leaves, of means for gripping the stem butts of leaves and drawing them through said stripping mechanism to strip them, rotary gripping mechanism for seizing the stems of leaves which have broken off from the stem butts gripped by said means and pulling said stems into said stripping mechanism to strip the same, and a device for scoring at a predetermined length the stems of the leaves drawn into the stripping mechanism by said means so that each unbroken stem will be broken off at its scored portion.

8. The combination with mechanism for stripping the lamina from the stems of tobacco leaves, of means for gripping the stem butts of leaves and drawing them into said stripping mechanism to strip them, and a device for scoring at a predetermined length the stems of the leaves drawn into the stripping mechanism by said means so that the stems will be broken off at

their scored portions when the latter enter said stripping mechanism, said device being situated adjacent said mechanism on the side remote from said gripping means, and means for operating said device to score the stems of said leaves at 5 said length while said carded surfaces are moving relative to said gripping means to strip the laminae from the stems being scored.

9. In a tobacco stemming machine, the combination with a butt-stripping unit, of mechanism for advancing leaves into the range of action of said butt-stripping unit, carded traveling, endless surfaces adapted to strip the lamina from the stems of leaves drawn therebetween, and means for gripping the stem butts of the 15 leaves after they have been subjected to the action of said butt-stripping unit and drawing them between said carded surfaces, said butt-stripping unit including a pivoted bed, an electric motor mounted on said bed, a set of superimposed 20 carded rolls extending along the path of leaves advanced by said mechanism and supported from said bed, said rolls being driven from said motor and sufficiently spaced to admit therebetween the butts of leaves advanced by said mechanism and thereby strip the same, whereby said bed may be swung outwardly on its pivot to move said rolls out of operative position.

10. The combination with a butt-stripping unit, of mechanism for advancing tobacco leaves 30 into the range of action of said unit, said unit including a pivoted bed, an electric motor mounted on said bed, a set of superimposed carded rolls extending along the path of leaves advanced by said mechanism and supported from said bed, 35 said rolls being driven from said motor and sufficiently spaced to admit therebetween the butts of leaves advanced by said mechanism and thereby strip the same, whereby said bed may be swung on its pivot to move said rolls out of operative 40 position.

11. The combination with opposed carded traveling, endless surfaces adapted to strip the lamina from tobacco leaves drawn therebetween, of means for gripping the stem butts of leaves 45 and drawing them between said carded surfaces, said carded surfaces including belts having opposed runs diverging from said means and adapted to strip leaves drawn therebetween by said means, motor-driven and idler pulleys over which 50 said belts are looped, devices for transversely adjusting said driven and idler pulleys relative to the stem butts of leaves gripped by said means, said means including a pair of traveling, endless cables having opposed runs adapted to grip leaves 55 therebetween, a stationary bar supporting one of said runs, a spring-pressed bar urging the other of said runs towards said stationary bar to clamp the leaves on the cable run passing over said stationary bar, means for retracting said spring-pressed bar from operative position, and a device for latching the spring-pressed bar in either 60 operative or retracted position.

12. The combination with a pair of traveling, 65 endless cables having opposed runs, of a stationary bar supporting one of said runs, a spring-pressed bar urging the other of said runs towards said stationary bar to clamp stem butts on the cable run passing over said stationary bar, means 70 for retracting said spring-pressed bar from operative position, and a device for latching the spring-pressed bar in either operative or retracted position.

13. In a tobacco stemming machine, the com- 75

- bination with butt-stripping mechanism, of mechanism for advancing leaves into the range of action of said butt-stripping mechanism, carded traveling, endless surfaces adapted to strip the lamina from the stems of leaves drawn therebetween, means for gripping the stem butts of the leaves after they have been subjected to the action of said butt-stripping mechanism and drawing them between said carded surfaces, a 10 rotary disk having sets of opposed grippers co-acting to seize the stems of leaves which have broken off from the stem butts gripped by said means and pull said stems between said carded surfaces to strip them, and a set of traveling, 15 endless belts arranged to receive any unstemmed leaves from between said carded surfaces and carry them away to separate the same from the stemmed leaves.
14. In a tobacco stemming machine, the combination with butt-stripping mechanism, of mechanism for advancing leaves into the range of action of said butt-stripping mechanism, carded traveling, endless surfaces adapted to strip the lamina from the stems of leaves drawn therebetween, means for gripping the stem butts of the leaves after they have been subjected to the action of said butt-stripping mechanism and drawing them between said carded surfaces, and 20 a traveling member having sets of relatively movable grippers coacting to seize the stems of leaves which have broken off from the stem butts gripped by said means and pull said stems between said carded surfaces to strip them.
15. In a tobacco stemming machine, the combination with butt-stripping mechanism, of mechanism for advancing leaves into the range of action of said butt-stripping mechanism, carded traveling, endless surfaces adapted to strip the lamina from the stems of leaves drawn therebetween, means for gripping the stem butts of the leaves after they have been subjected to the action of said butt-stripping mechanism and drawing them between said carded surfaces, a 25 rotary disk having sets of opposed grippers coacting to seize the stems of leaves which have broken off from the stem butts gripped by said means and pull said stems between said carded surfaces to strip them, a device for scoring at a predetermined length the stems of leaves drawn 30 between said carded surfaces by said means so that each unbroken stem will be broken off at its scored portion, and a set of traveling, endless belts arranged to receive any unstemmed leaves from between said carded surfaces and carry 35 them away to separate the same from the stemmed leaves.
16. In a tobacco stemming machine, the combination with leaf gripping and forwarding means, of a stripping unit, said unit including a pivoted bed, stripping mechanism supported on said bed for movement into and out of position to operate on leaves advanced by said means, and a motor also mounted on said bed to drive said stripping mechanism.
17. In a tobacco stemming machine, the combination with a pair of flexible endless members having opposed and centrally carded surfaces with non-carded portions to either side thereof, of a series of opposed grippers adapted to enter 45 between said non-carded portions to grip stems projecting from said carding, and means for operating said grippers to seize said stems and pull the same in a direction diverging from the path of movement of said members.
18. In a tobacco leaf stemming machine, the combination with a pair of flexible endless traveling members carrying opposed stripping elements for stripping and simultaneously advancing the leaves, primary means for gripping the stems of leaves advanced by said members, said members and means having relative movement to pass the elements along the stems to strip the leaves, and secondary means for gripping and pulling out 50 the stems of leaves left in said elements by said primary means, said secondary means including a series of gripper jaws traveling in an endless path diverging from the path of said members.
19. In a tobacco stemming machine, the combination with butt-stripping mechanism, of mechanism for advancing leaves into the range of action of said butt-stripping mechanism, carded traveling, endless surfaces adapted to strip the lamina from the stems of leaves drawn therebetween, means for gripping the stem butts of the leaves after they have been subjected to the action of said butt-stripping mechanism and drawing them between said carded surfaces, and 55 a traveling member having sets of opposed grippers coacting to seize the stems of leaves which have broken off from the stem butts gripped by said means and pull said stems between said carded surfaces to strip them, and a device for scoring at a predetermined length the stems of leaves drawn between said carded surfaces by said means so that each unbroken stem will be broken off at its scored portion.
20. In a tobacco stemming machine, the combination with butt-stripping mechanism, of mechanism for advancing leaves into the range of action of said butt-stripping mechanism, carded traveling, endless surfaces adapted to strip the lamina from the stems of leaves drawn therebetween, means for gripping the stem butts of the leaves after they have been subjected to the action of said butt-stripping mechanism and drawing them between said carded surfaces, a 60 traveling member having sets of opposed grippers coacting to seize the stems of leaves which have broken off from the stem butts gripped by said means and pull said stems between said carded surfaces to strip them, and a device for scoring at a predetermined length the stems of leaves drawn between said carded surfaces by said means so that each unbroken stem will be broken off at its scored portion.
21. The combination with carded traveling, endless surfaces adapted to strip the lamina from the stems of tobacco leaves drawn therebetween, of means for gripping the stem butts of leaves and drawing them between said surfaces to strip them, a member provided with a plurality of sets 65 of gripper jaws for seizing the stems of leaves which have broken off from the stem butts gripped by said means and pulling said stems between said carded surfaces to strip them, and a device for scoring at a predetermined length the stems of the leaves drawn between said carded surfaces by said means so that each unbroken stem will be broken at its scored portion.
22. In a tobacco stemming machine, the combination with a butt-stripping unit, of mechanism for advancing leaves into the range of action of said butt-stripping unit, carded traveling, endless surfaces adapted to strip the lamina from the stems of leaves drawn therebetween, and means for gripping the stem butts of the leaves after they have been subjected to the action of said butt-stripping unit and drawing them between said carded surfaces, said butt-stripping unit including a pivoted bed, a set of superimposed carded rolls extending along the path of leaves advanced by said mechanism and supported from said bed, means for driving said rolls, said rolls being sufficiently spaced to admit therebetween the butts of leaves advanced by 70
- 75

said mechanism and thereby strip the same, whereby said bed may be swung outwardly on its pivot to move said rolls out of operative position.

23. The combination with a butt-stripping unit, 5 of mechanism for advancing tobacco leaves into the range of action of said unit, said unit including a pivoted bed, a set of superimposed carded rolls extending along the path of leaves advanced

by said mechanism and supported from said bed, means for driving said rolls, said rolls being sufficiently spaced to admit therebetween the butts of leaves advanced by said mechanism and thereby strip the same, whereby said bed may be swung 5 on its pivot to move said rolls out of operative position.

RUPERT E. RUNDELL.
